UNITED STATES PATENT OFFICE.

HERMAN G. GROSSE, OF CHICAGO, ILLINOIS.

IRONING MACHINE.

Application filed July 21, 1924. Serial No. 727,382.

To all whom it may concern:

Be it known that I, HERMAN G. GROSSE, a citizen of the United States, and a resident of Chicago, in the county of Cook and State of Illinois, have invented certain new and useful Improvements in Ironing Machines; and I do hereby declare that the following is a full, clear, and exact description thereof, reference being had to the accompanying drawings, and to the characters of reference marked thereon, which form a part of this specification.

This invention relates to improvements in ironing machines of that type including a rotary padded roll between which and a heating shoe the clothes to be ironed are fed and pressed, the roll being held by pressure towards the shoe to effect the pressing of the work which is fed between the roll and shoe by the tractive effort of the roll.

In machines of this character, the padded roll is mounted to be movable toward and from the concave face of the shoe and is rotatable at its top toward the shoe to carry or feed the work between the roll and shoe, there being driving connections extending from the machine base to the roll to effect the rotation of the roll in one direction.

Among the objects of the invention is to produce what may be termed a dual, open-ended machine, in that the roll and shoe and the supporting and driving mechanism for the roll are so related that the clothing to be ironed, hereinafter termed work, can be fed between the roll and shoe entirely across the length of the roll and equally well fed between the roll and shoe at either end of the roll; due to the fact that there are no projecting parts at the ends of the roll which will prevent free approach of the work to the space between the roll and shoe, and due also to the fact that the driving gearing which rotates the roll is not exposed at the roll end and, therefore, avoids danger of the work being caught in the driving gearing.

In machines of this type, it is desirable when ironing symmetrical articles of work, such as shirts, waists and the like, to be able to alternately insert the work between the roll and shoe at both ends thereof, and it is also desirable in ironing work that is of larger dimensions than the length of the roll and shoe to permit part of the work to extend beyond either end of the roll and shoe. These different approaches of the work to

the roll and shoe, and other approaches which are encountered in the operation of a machine of this character, greatly simplifies the ironing operation and permits the operator to perform all of the ironing operation without moving far from a central operating position in front of the machine.

A further object of the invention, subordinate to and directed towards the main feature above mentioned, is the employment of supporting means by which the roll is supported and moved bodily towards and from the shoe, constructed to afford a housing for a train of gears which connects the roll with driving power below. In such machines, it is desirable that the roll shall have a continuous pressing surface, and driving power is, therefore, communicated to one or both ends of the roll. In machines of ordinary size, such driving power can be communicated to one end of the roll, and this phase of my invention contemplates the construction of one of the swinging arms which supports the roll and permits movement thereof towards and from the shoe, as a hollow element to constitute a housing or chamber to enclose the driving gears.

A further and specific object of the invention is to provide means for hinging the roll supporting and operating arms to the machine frame.

A further object of the invention is to provide a novel means of connecting the last gear of the driving train to a gear which rotates with the roll.

Further objects of the invention are to further simplify and improve ironing machines of this general type, and the invention is described in the specification with respect to a preferred embodiment thereof, and is particularly pointed out in the appended claims.

In the drawings: Figure 1 is a front elevation of an ironing machine embodying my invention, broken away, to indicate indefinite length.

Figure 2 is an end view thereof.

Figure 3 is a section detail which illustrates the gear mechanism for connecting the gear train to the roll, taken on the indirect line 3-3 of Figure 2.

Figure 4 is a horizontal detail section on the general line 4-4 of Figure 2, with parts omitted and other parts broken away.

As shown in the drawings, 10 designates the base of the machine, the ends of which

- are connected by the tie elements 11, and preferably having a back wall. The super-frame embraces end pieces or castings 12 supported above and in the general plane of the end pieces of the subframe or base 10; and said upper end frame pieces are formed with rear, upward extensions 13 which carry a known form of fixed shoe 14 that may be heated by gas or electricity.
- 10 15 designates a padded, cylindric roll that lies in front of and is opposed to the concave ironing face of the shoe 14. 16, 16 designates mounting and pressure arms for the roll, said arms being adapted to support 15 the weight of the roll and to move it towards and from the shoe. 17 designates a table over which the work is fed to the top of the roll and thence into the space between the roll and the shoe; the work being guided into said space by an upstanding lip 18 constituting part of the casting of the shoe. The table 17 is normally horizontal and flush with the upper surface of the roll. It is pivoted at 19 to extensions of the arms and 25 is normally held in its feeding position by springs 20.
- 21 designates the motor which drives the roll. It is wall-mounted on one of the end frames of the base 10. The motor belt drives 30 through a pulley 23, a shaft 24 which has a worm gear train connection to a countershaft 25 arranged above and at right angles to the shaft 24. Said countershaft 25 extends outwardly through and has bearing in 35 a bushing 26 which is seated in the hub 27 of the right hand roll support and pressure arm 16, said hub being rotatably supported in the end frame 12. Said countershaft 25 is driven and controlled by the driving 40 mechanism illustrated in the co-pending application of Christopher Groen, Serial Number 733,939 filed on the 25th day of August, 1924. Said driving mechanism embraces, so far as it is necessary to disclose it here, a 45 clutch mechanism which is operated to connect and disconnect the rotative countershaft 25 to the driving gear train for the roll.
- 28 designates the lowermost gear and 29 the uppermost gear of said train, and 30, 50 30 designate the intermediate gears of the train. The right hand arm 16 is hollow to produce a chamber or enclosure for the gear train, and said gears are rotatably supported on shafts fixed in the walls of the hollow 55 arm. Said hollow arm, as herein shown, embraces a recessed casting constituting the major portion thereof, and a thinner plate 31 constituting the outer side of the arm, and is detachably fixed to the casting by the 60 screws shown in Figure 2. The said gear 28 is coaxial with the pivotal axis of the arms 16 and the axis of the shaft 25, whereby pivotal movement of the arm can be effected 65 to move the roll toward and from the shoe 65 while maintaining the gear train in opera-

tive driving relation to driving power and the roll.

The first gear 28 of the train is rotatable on the shaft 25, and is adapted to be connected to and disconnected from the counter- 70 shaft 25 by a clutch which includes an annular series of laterally directed clutch teeth 32 on the gear 28 adapted to engage with similar clutch teeth 33 of a clutch collar 34, endwise slidable on a sleeve 38 through the 75 medium of a clutch finger 35 that is carried by an endwise movable, rotative shaft 36 mounted in the machine frame and controlled by a knob 37. Said clutch collar is endwise slidable on but rotates with a 80 sleeve 38, as through the spline shown in Figure 4, the sleeve being fast to said countershaft 25. The detail of this clutch is shown in said Groen application and need not be more fully referred to here except 85 to say that the sleeve 38 fits over the outer end of the countershaft 25 and is provided with a central opening to receive the reduced, screw-threaded extremity of said countershaft, whereby it is fastened to the 90 countershaft; the hand of the thread being such relative to the normal direction of rotation of the shaft 25 as to hold the sleeve in place on the countershaft.

The terminal gear 29 of the driving gear 95 train is fixed to a stub shaft 39 that is mounted to rotate in a bushing 40 which is seated in a bore formed in an inwardly directed extension 41 at the upper end of the arm 16. Said shaft 39 is fixed to or 100 made integral with the pinion 42 which meshes with an internal gear 43 that is seated a distance within and is fixed to the hollow end of the roll; said internal gear being integral with the ring 44 that is made 105 part of a spider or head 45 which itself is integral with bearing tube 46 axially in the drum and in which is mounted a fixed shaft 47. Said shaft 47 is shown as fixed in place by means of a screw stud 48 that is screwed 110 through the extension 44 bored to receive the outer end of the shaft 47, with the screw bearing at its inner end against said shaft. The roll is rotatably supported on said shaft 47 through the medium of a bushing 48; and 115 a spacer 49 spaces said arm extension 41 from the roll bearing tube 46.

With this construction, it will be apparent that shaft 47 is carried by the upper 120 ends of the arms 16, the connection of said shaft with the left hand arm being generally similar to that illustrated in Figure 3, and that the roll is free to rotate about said shaft and is rotated by the motor through the gear train described. The roll 125 may be held pressed towards the shoe by mechanism illustrated in the aforesaid Groen application and may also be retracted from the shoe by means of the latter mechanism. It will be noted from an inspection 130

of Figures 1, 2 and 3 that the geared end of the roll is free from projections, either driving or other structural projections, of such nature as to prevent easy approach of the work to the space between the roll and shoe, said geared end of the roll being as free in this regard as the other end of the roll. Therefore, both ends of the roll are open to receive the work with equal facility and convenience, brought thereto by an operator standing in front of and centrally with respect to the machine. It will also be observed that the open gear end of the roll is made possible within compact compass by making the adjustable supporting and pressure arm of the roll hollow to constitute a casing or a guard for the driving gear train. So far as this aspect of the invention is concerned, the construction at the gear end of the roll amounts to more than a mere guard for the gear train, inasmuch as the roll supporting and pressure arm performs the plural functions of pivotally supporting the roll to permit it to be swung towards and away from the shoe and encloses the gear train within what may be termed normal end limits of the machine. The construction, therefore, having these plural characteristics, is simplified and is compact and attractive. Moreover, by mounting the gear train in the swinging arm, movement of the roll towards and from the shoe does not interfere with the driving functions of the gear train when the roll is moved towards or from the shoe.

The insertion of the internal gear 43, adapted to mesh with the pinion 42 which is rotated by the terminal gear of the train and the insetting of the arm extension 41 into the open gear end of the roll, also contributes towards compactness and ready adaptation of the open end feature of the geared end of the roll. If desired, driving power can be transmitted to both ends of the roll with the same facility in respect of an open ended roll, compactness and guarding of gears, as with a single driving gear train.

I claim as my invention:

1. An ironing machine comprising a shoe and a rotatable roll, supporting members for said shoe and roll constructed and arranged to leave the space between the shoe and the roll open at each end of the roll, the supporting members for the roll having their outer faces lying close to the ends of the roll at and below the latter to permit work to extend past said members and into the space between the shoe and the roll without meeting any obstruction, and driving means for the roll extending through one of the roll-supporting members.

2. An ironing machine comprising a shoe and a rotatable roll, supporting members for said shoe and roll constructed and arranged

to leave the space between the shoe and the roll and the space below the roll open at each end of the roll, and a driving train for the roll extending through and housed by one of said members. 70

3. In an ironing machine, a base, a stationary shoe mounted a considerable distance above the base, a rotatable roll arranged in front of the shoe, supports for the shoe rising from the base and lying wholly in rear of the shoe, supports for the roll rising from the front of the base at each end of the roll and having their outer sides lying wholly within vertical planes located near the ends of the roll, and driving means for the roll 80 lying within the plane of the outer face of one of the roll-supports. 75

4. In an ironing machine, a base, a shoe located a considerable distance above the base, a rotatable roll lying in front of the shoe, means rising from the base and lying wholly in rear of the shoe for supporting the latter, two swinging arms extending upwardly from the front of the base in front of and adjacent to each end of the roll, said arms having rearward projections at their upper ends extending into the vicinity of the axis of the roll to support the latter, and a train of gearing for rotating said roll extending upwardly through one of said arms. 90 85

5. An ironing machine comprising a shoe, and an opposing rotative roll, pivotally mounted supporting and pressure arms for carrying said roll, and a gear train for driving said roll, comprising a power driven gear coaxial with the pivot of said arms, said train being carried by one of said arms. 95 100

6. In an ironing machine, a stationary shoe, a rotatable roll lying in front of the shoe, supports extending downwardly from the roll in front thereof and from the shoe in rear thereof, the supports for the roll having rearward extensions at their upper ends and lying wholly above the bottom of the roll to support the roll, said extensions having their outer faces lying close to the ends of the roll, and driving means for the roll lying inside of the plane of the outer face of one of said extensions. 105 110

7. An ironing machine comprising a shoe and a rotatable roll arranged one in front of the other, and supporting and driving means for the roll and supporting means for the shoe disposed away from the interspace between the shoe and the roll to leave the ends of the latter open and so located and shaped as to leave a deep unobstructed space, open at the ends, extending from beneath the shoe underneath the roll to the remote side of the roll. 115 120

8. In an ironing machine, a supporting member, a shoe located a considerable distance above said member, a roll lying in front of the shoe, means rising from said member and lying wholly in rear of the shoe for sup- 125 130

porting the latter, two swinging arms extending upwardly from said member and lying wholly in front of the roll and with the outer surfaces close to the ends of the 5 roll, said arms having rearward projections at their upper ends lying wholly above the bottom of the roll and extending into the

vicinity of the axis of the roll to support the latter.

In witness whereof I claim the foregoing 10 as my invention, I hereunto append my signature this 23rd day of June, 1924.

HERMAN G. GROSSE.
